J. C. Whittin.

Machine for Spreading and Picking Cotton.

Patented Jul. 20, 1832.

John C. Whiting of Northbridge Massachusetts
Letters Patent.

The Schedule referred to in the Letters Patent and making
part of the same containing a description in the words of the said
John C. Whiting himself of his improvement in the machine
for spreading and picking cotton.

To all whom these presents shall come. Be it known that I John
Whiting of Northbridge in the County of Worcester and State of Massachusetts
have invented a new and useful improvement in the spreading and picking
machine in the preparation of cotton for the carding and that the following is an
exact description of the construction of said machine and of the improve-
ment invented by your petitioner for which he now requests Letters Patent of the
United States. Said machine consists of a cast iron, or wooden frame
of sufficient length to contain the movements of the same including the ap-
pros feeding cloth on which the cotton is placed in its raw state. Said frame
is denoted by the orange colour in the annexed drawing marked A. A
of three wire cylinders placed horizontally on the same. Constructed with a
flange or heading at each end of them of about two or three inches in width
so as to retain the sheet of cotton or lap in suitable form and with a
smooth compact edge in passing through the machine. Said cylinders
are marked B.B.B; of three beaters, one of which is placed before each
of the wire cylinders marked C.C.C. of eight feeding Rolls, two pair of which
are marked D.D. are placed between the iron or feeding cloth, and the
first beater at about half an inch distance from each other, the pair next
the Roll to revolve with a greater speed than the other so as to stretch the
cotton moderately and give a right direction to the fibre or staple. The
other two pairs marked E.E. are placed in front of the remaining two beat-
ers. Of three wooden rolls or drums marked F.F.F. resting horizontally on
each of the wire cylinders so as to press down the cotton as it passes over
the cylinders; after pair of rollers marked G.G. one of which is placed
in the rear of the two first wire cylinders so as to conduct the cotton
from the first and second cylinders to the third and third beaters, of two

July 20, 1832

pair of rolls marked I.I. to conduct the cotton from the third cylinder to a wooden or metal roll marked K in which the cotton is rolled ready for the operation of the card. Said last mentioned roll rests in its operation on two other rolls marked I.I. that compress the cotton and make it more compact and convenient for subsequent operations.

At each end of the three last rolls are placed cast iron plates or boards with smooth surfaces so as to keep the tips or rolls of cotton of the desired and uniform width. Said movements are all to be geared excepting the beaters which are operated by belting. So much of said movements as are above the frame that supports them are caused so as to prevent any fly or waste of cotton. The improvement in said spreading and picking machine invented by the Petitioners, and for which he requests Letters Patent is in the application of gearing to the several movements instead of Belts and of the flange or rim to the ends of the several wire cylinders.
